Inventor:
John P. Lyman,
By J. Wm. & J. Wm. Atty.

UNITED STATES PATENT OFFICE

JOHN P. LYNN, OF CHICAGO, ILLINOIS, ASSIGNOR TO DUR-O-LITE PENCIL COMPANY, OF CHICAGO, ILLINOIS, A CORPORATION OF ILLINOIS

CLIP FOR POCKET INSTRUMENTS

Application filed December 30, 1929. Serial No. 417,291.

This invention which relates to a clip for pocket instruments, such as pens, pencils, and the like is concerned particularly with a construction which is simple and inexpensive to produce, which is strong and durable in service, and which is easily and securely attachable to the body of the instrument to which it is connected; and the present improvements were first disclosed in my application for patent on pencils, filed December 7, 1927, under Serial No. 238,309, of which the case is a division.

In the accompanying drawings—

Figure 1 shows by way of exemplification a pencil, partly in elevation and partly in longitudinal section, to which is attached a clip embodying the improved features of my invention;

Fig. 2 is a fragmentary perspective view of the clip per se;

Fig. 3 is a similar view of a slightly modified construction of the clip; and

Fig. 4 is a fragmentary view in elevation of a pencil body adapted for the attachment thereto of the present clip.

In the instrument shown, which is a mechanical pencil, I may combine separably with a body A a relatively rotatable part such as the tip B. The body is shown as provided with a slotted axial bore 5 through which may slide non-rotatably a screw-threaded propeller 6 having a head 7 at one end thereof. This bore in the body extends upwardly from its lower end for a distance sufficient to accommodate the propeller throughout its entire range of movement. A lead is advanced through the tip in response to forward movement of the propeller.

The upper pencil end may be chambered as at 8 to provide a magazine for extra leads C. The closure for this magazine may consist of a cup-like retainer 9 split to provide spaced jaws which engage an eraser D, the retainer being supported within a ferrule 10 which extends down over the sides of the pencil adjacent its upper end. Preferably the outer surface of the pencil body is recessed sufficiently to accommodate this ferrule in flush relation with the remainder of the body. The ferrule is detachably fitted to the pencil

end so as to permit access to the lead chamber therewithin.

The clip of my invention is applicable to a pocket instrument of which the construction described is merely typical. As shown, the clip comprises a spring arm 11 which may terminate in a ball 12 adapted to rest against the outer side of a pocket. At its upper end the arm is inset in the form of a head 13 through which is a hole 14. At its upper extremity the head is provided with one or more laterally extended teeth 15, two being the number which is shown. A screw 16 having a head 17 is entered through the hole 14 to effect a threaded connection within an opening 18 in the pencil body. These openings may be aligned with a screw threaded hole formed in a lining 19 which optionally is fitted interiorly of the chamber 8. By tightening the screw to the position shown in Fig. 1, its threads take hold with those of the body and/or lining and at the same time the teeth 15 enter or bite into the instrument body so as to prevent swinging movement of the clip around the screw as an axis. This manner of attachment not only holds the clip fixedly in place, but also, in case a lining 19 is used, secures the latter firmly within the chamber.

The teeth 15 may be slightly pointed to bite into the instrument body, or as an alternative construction they may be in the form of a single blunt tooth 15', as suggested in Fig. 3, adapted to enter a preformed slot 20' in the body of the instrument. In the latter form, the tooth consists merely of a turned end which fits within the slot 20' in such a manner as to prevent swinging movement of the clip when held in place by the screw 16. The parts shown in Figs. 3 and 4 correspond largely with those shown in the remaining figures and are designated by similar reference numerals to which is added a prime (') in each instance.

The improved clip herein described is advantageous in that it is simple, strong, easily formed and applied in place, and susceptible of receiving ornamentation or other markings for conspicuous display.

I claim:

In a pocket instrument having a chambered body and a sleeve forming a lining therefor, the body and lining having registering openings with threads formed in the lining opening, a clip having an apertured head with an inturned tooth at one end thereof adapted to bite into the body of the instrument, and a screw passing through the openings in the clip head and instrument body for screw-threaded engagement with the threaded opening in the lining, whereby to draw the clip head toward the lining and inbed the tooth into the body to immovably secure the units together.

In testimony whereof, I have hereunto set my hand and affixed my seal this 27th day of December, 1929.

JOHN P. LYNN.
